HANDLE OR THE LIKE

Vytant P. Aleks, Rockford, Ill., assignor to National Lock
Co., Rockford, Ill., a corporation of Delaware

Filed Mar. 30, 1964, Ser. No. 79,240

Term of patent 14 years

(Cl. D10—8)

Fig. 1

Fig. 2

Fig. 3

Fig. 4

Fig. 5

FIG. 1 is a top plan view of a handle or the like embodying my new design;

FIG. 2 is a front elevational view thereof;

FIG. 3 is a rear elevational view thereof;

FIG. 4 is an end elevational view thereof; and

FIG. 5 is a cross sectional view thereof on the line 5—5 of FIG. 1.

I claim:

The ornamental design for a handle or the like, substantially as shown.
